UNITED STATES PATENT OFFICE.

ROLAND R. KELLY, OF WILLIAMSTOWN STATION, MASSACHUSETTS,
ASSIGNOR OF ONE-HALF TO DRAPER COMPANY, OF HOPEDALE,
MASSACHUSETTS, A CORPORATION OF MAINE.

CLOTH-ROLL SHAFT FOR LOOMS.

SPECIFICATION forming part of Letters Patent No. 718,949, dated January 20, 1903.

Application filed March 24, 1902. Serial No. 99,582. (No model.)

To all whom it may concern:

Be it known that I, ROLAND R. KELLY, a citizen of the United States, and a resident of Williamstown Station, county of Berkshire, 5 State of Massachusetts, have invented an Improvement in Cloth-Roll Shafts for Looms, of which the following description, in connection with the accompanying drawings, is a specification, like letters on the drawings representing like parts.

This invention has for its object the production of novel, simple, and efficient means for preventing longitudinal movement of the cloth upon the cloth-roll shaft in a loom as 15 the cloth is wound thereupon by the operation of the take-up mechanism.

In order to obtain smoothly-wound even rolls of cloth with parallel flat ends, various devices have been employed, said devices usually 20 acting as guides for the edges of the cloth as it passes around the shaft. I have in my present invention provided the cloth-roll shaft itself with means for engaging and preventing longitudinal movement of the cloth 25 upon the shaft while being wound, the said means being readily rendered inoperative when it is desired to withdraw the shaft from the completed roll of cloth. In accordance 30 with my invention several of the layers or windings immediately adjacent the shaft are firmly held from longitudinal movement, constituting a true and even core, as it were, on which the succeeding layers are readily wound.

35 The various novel features of my invention will be hereinafter described, and particularly pointed out in the following claims.

Figure 1 is a vertical transverse sectional view of a portion of a loom, taken at the inner side of one of the stands for the cloth-roll shaft, the latter being shown in section with one embodiment of my invention applied thereto; and Fig. 2 is an enlarged elevation and part section of the cloth-roll shaft, 45 the cloth-holding means thereon, and the roll of cloth wound upon said shaft.

Referring to Fig. 1, the loom-frame A, breast-beam B, take-up roll T, stands F, (only one being shown,) longitudinally slotted at f 50 for the rack-bars g^x, which at their upper

ends support the journals g of the cloth-roll shaft G, and the rack-gears g' in mesh with the rack-bars, may be and are all substantially as in United States Patent No. 610,636, dated September 13, 1898.

55

As shown in Fig. 2, the cloth-roll shaft G has a longitudinal recess or groove g² therein extending from near one end of the shaft to substantially its center, and a slightly-bent elongated arm g³ is fulcrumed in the recess 60 on a transverse pivot-pin g⁴. The inner end of the arm is turned out or provided with a substantially radial holding device, shown as a prong g⁵, which is normally maintained extended beyond the surface of the shaft by 65 a suitable spring, as s^x. The outer end of the arm is shown as bent oppositely to the prong to form a finger-piece g⁶, which extends through a hole g⁷ in the shaft and which intersects the recess g². In order to 70 limit the outward movement of the prong g⁵, the bottom of the recess is shown as slightly beveled at g⁸, Fig. 2, to support the outer end of the arm g³ near the finger-piece. When the web t of cloth passes around the take-up 75 roll T and thence to the cloth-roll shaft G, the holding device g⁵ enters the cloth and prevents it from moving longitudinally on the shaft, and the length of the prong is sufficient to penetrate a number of superposed 80 layers of the cloth immediately adjacent the shaft, as shown in the drawings. This serves to anchor or hold the cloth firmly while the inner portion or core is being laid upon the shaft, so that there can be no longitudinal 85 movement of the roll C of cloth during the winding thereof. When in the rotation of the shaft G the prong bears against the surface of the take-up roll, the spring s^x yields temporarily, so that the smoothness of the 90 winding is not interrupted. After the desired length of cloth has been wound and cut off from the web the roll of cloth and its shaft G are removed, and when it is desired to withdraw the shaft from the roll C the attendant 95 presses on the finger-piece g⁶, thereby tilting the arm g³ on its fulcrum, compressing the spring s^x, and the prong or holding device g⁵ is retracted into the recess g² and withdrawn from the cloth, so that the shaft can be 100

pulled out of the roll C and replaced in the loom.

Having fully described my invention, what I claim as new, and desire to secure by Letters 5 Patent, is—

1. A longitudinally-recessed cloth-roll shaft for looms, a radially-movable, spring-controlled prong mounted thereon to engage and prevent longitudinal movement of the cloth 10 as it is wound upon the shaft, and means pivotally mounted in the recess to retract said prong against the action of its spring to release the roll of cloth and permit withdrawal of the shaft, said means having a finger-piece 15 accessible at one end of the shaft, whereby the said means may be manually operated.
2. A cloth-roll shaft for looms having a lon-

itudinal recess therein, an arm fulcrumed in said recess and having a cloth-engaging device, a spring to normally maintain said 20 device extended beyond the surface of the shaft, to engage and prevent longitudinal movement of the cloth as it is wound upon the shaft, and a finger-piece on said arm at its outer end, to rock the arm and withdraw 25 the cloth-engaging device from the cloth.

In testimony whereof I have signed my name to this specification in the presence of two subscribing witnesses.

ROLAND R. KELLY.
